[73] Assignee: Sokkia Co., Ltd., Tokyo, Japan

[57] CLAIM

[**] Term: 14 Years

The ornamental design for a support base for a laser light range meter equipped with a telescope, as shown and described.

[21] Appl. No.: 45,154

DESCRIPTION

[22] Filed: Oct. 11, 1995

FIG. 1 is a front elevational view, showing my new design;
FIG. 2 is a rear elevational view thereof;
FIG. 3 is a right side elevational view thereof;
FIG. 4 is a left side elevational view thereof;
FIG. 5 is a top plan view thereof;
FIG. 6 is a bottom plan view thereof; and,
FIG. 7 is a reference view showing the state of use thereof.
The broken line showing the remaining parts of a support base for a laser light range meter equipped with a telescope is for illustrative purposes only and forms no part of the claimed design.
